UNITED STATES PATENT OFFICE.

ALFRED SHELDON, OF NEW ORLEANS, LOUISIANA.

FUEL PUMP.

Application filed July 5, 1922. Serial No. 572,826.

To all whom it may concern:

Be it known that I, ALFRED SHELDON, a citizen of the United States, residing at New Orleans, in the parish of Orleans and State of Louisiana, have invented new and useful Improvements in Fuel Pumps, of which the following is a specification.

My present invention pertains to internal combustion engines and the like and it contemplates the provision of a device for supplying a large range of fuel from 18° Baumé up, including kerosene and distillates, to such engines.

The invention further contemplates the provision of a fuel measuring pump and spray nozzle for use in connection with each cylinder of an engine whereby carbon deposits will not be left on the piston or in the combustion chamber. With slight modification existing types of commercial engines may be equipped with my device.

Other objects and characteristic features will be fully understood from the following description and claims when the same are read in connection with the drawings accompanying and forming part of this specification, in which—

Figure 1 is a view illustrating in side elevation my device as applied on a cylinder that is shown in section.

Figure 2 is a longitudinal sectional view of the fuel pump and atomizer.

Figure 3 is a side elevation of the device and looking from the fuel supply pipe.

Similar numerals of reference designate corresponding parts in all the views of the drawings.

My novel device comprises the atomizer body or casing 1 having the depending integral casing 2 that is threaded whereby it may be secured in the cylinder head casing preferably above the combustion chamber 43 and directly above the piston head 46.

The casing 2 has an interior bore 3 of a diameter that produces a clearance between itself and the spray needle 4 and said needle moves within the casings 1 and 2 and is provided at its lower end with spiral grooves for increasing the turbulence of the fuel to the chamber.

A threaded plug 7 having a passage 6 therein is secured in the end of the casing 2 and the nozzle is provided with the tapered end that normally seats in the passage 6 to prevent fuel from gaining access to the

combustion chamber. The casing 2 is provided with the bur 2^a to permit of the adjustment, with a wrench, of the casing on the chamber. The stem of the nozzle 4 is increased in diameter at its upper end as indicated by 4^a and is surrounded by a gland 15. The upper portion 4^a of the needle 4 enters a hood 18 that is provided with a spring 17 confined in the hood by means of a projection 18' formed integral within the upper end of the hood 18. The projection 18' seats in and bears against the upper end of the spring 17.

A bell crank 20 on the shaft 21 is provided with a portion 19 that rests between the nuts 16 on needle 4 and the gland 15. Manifestly rocking of the arm 20 will move the needle upwardly from its normal inoperative position. At its lower end the arm 20 is provided with a roller 23 and a shoe or abutment 26 that is adapted upon rocking of the arm 20 to actuate an air bell crank arm 27 that is provided with a portion 32 confined between the nuts 33 of the air control stem 34. This stem travels in a bore 35 of the body 1 parallel with the needle 4 and said stem is provided with the tapered upper end 37 that bears against a check ball 38. This ball on upward movement of the stem or plunger 34 seats in the air inlet 39 to prevent further passage of air to the by-pass 36. The crank 20 is fulcrumed at 21 on the support 22 while the air crank 27 is fulcrumed also.

Arranged adjacent the roller 23 of arm 20 is cam 24 on shaft 25 and when the projection of the cam strikes the roller 23 the crank arms 20 and 27 will be placed in operation.

An oil or fuel inlet supply pipe 8 enters the body 1 and a chamber having a passage 9 that enters a chamber 10 in which is provided a fuel check ball 9" backed by the spring 12. At the upper end the chamber 10 is provided with a pet cock 14 and a by-pass 13 permits passage of fuel from chamber 10 to clearance 3 of needle 4.

The regular well known spark plug threaded in the cylinder chamber as indicated at 44 is employed and for purposes of illustration I have shown the valve head 45 in the cylinder.

It will be noted that a small bell crank 27 arranged on the shaft 30 and having the eccentrically arranged cam 29 may be em-

ployed and by moving the handle 41 of crank 28 in an arc of 30° the air can be adjusted to the degree desired.

The handle may be passed over and retained above the openings 42.

The device may be employed on two or four cylinder engines with equal facility and in multiple cylinder engines the fuel pumps are spaced evenly around the one actuating 10 cam.

In practice the actuating cam strikes the roller on the large bell crank and this crank slightly lifts the spray needle 4. The action also operates small bell crank admitting 15 a small charge of compressed air by-pass. Air is supplied in a very small volume and the fuel will be sprayed into the explosion chamber in an even and steady manner.

Manifestly by decreasing the tension of 20 spring on needle 4 great flexibility at all speeds is attainable and tests have demonstrated that a spark plug is used for the initial ignition and after a few seconds the spark is cut off. The device entirely eliminates 25 carbon in the combustion chamber or other place and by means of timing and the peculiar shape of cam, a slow burning or partly explosive impulse can be had and the heavy explosive shock eliminated.

30 With my device no water injection is necessary and no unburned fuel permitted to condense and pass the rings thus timing the sump oil; moreover a small volume of compressed air is required for spraying and 35 only enough to create turbulence and penetration.

Absolutely no refrigeration takes place and the pump measures the fuel for each charge without glands.

40 The device is simple in construction and efficient and prevents choking of the needles as in the cam and bell cranks are positive in action and so arranged that ready adjustment of parts may be made.

45 Having described my invention, what I claim and desire to secure by Letters Patent is:

1. In a fuel pump and atomizer, the combination of a large bell crank arm, a small 50 bell crank arm fulcrumed on the same shaft as the first arm, a body member adjacent the arms, an air passage formed in the body, a plunger arranged in the passage and actuatable by the small crank arm, a fuel passage 55 arranged in the body, a needle stem movable in the fuel passage, and actuatable by the large arm, and a cam adapted to impart movement to the crank arms.

2. In a fuel pump and atomizer, the combination of a casing, a fuel supply passage 60 in the casing, an air duct formed in the cas-

ing, a piston for controlling passage of air to the casing, a stem formed integral on the casing, a needle piston having channels in its lower end and movable within the casing 65 and stem; said piston being slightly decreased at one end to form a clearance for fuel film, a spring for regulating the pressure on the needle piston, crank arms fulcrumed adjacent the casing and actuatable one 70 from the other, and a cam for actuating one of the arms; said arm being adapted to actuate the first and second pistons, respectively.

3. A device for controlling and measuring the flow of fuel to a combustion chamber comprising a body portion, air and fuel inlets arranged in the body portion, means for regulating the pressure of the fuel and air within the body portion, a needle stem 75 arranged in the casing, a clearance formed at one end of the stem, a piston having a check ball arranged in the air chamber, a passage for permitting passage of air and fuel to the clearance, a rocker arm fulcrumed adjacent the body portion; one of the arms contacting with the stem and the other of the arms with the piston for elevating the piston and stem, and means arranged adjacent the arms for actuating the 80 arm synchronously.

4. In a fuel supply and measuring device for use in connection with two or four cycle internal combustion engines and the like, the combination of a casing, a stem formed on 95 the casing and adapted to be threaded on a cylinder casing above the head thereof, an atomizer plunger movable in the casing and stem for controlling passage of fuel through the casing, a plunger arranged parallel of 100 the first plunger within the casing, a bell crank arm removably secured to the first plunger adjacent the casing, and a second bell crank similarly arranged with respect to the second plunger, one of said arms being 105 actuatable and contacting with the first arm.

5. In a device for the purpose set forth, the combination of a casing having a lower depending portion, a stem movable in the 110 casing and having a clearance between its lower end and the casing, an air regulating stem arranged in the casing, means for moving the stems, and means for actuating the stem moving means.

In testimony whereof I have hereunto set my hand in presence of two subscribing witnesses.

ALFRED SHELDON
